UNITED STATES PATENT OFFICE.

LOUIS C. WESTPHAL, OF CHICAGO, ILLINOIS, ASSIGNOR TO S. KARPEN & BROS., OF CHICAGO, ILLINOIS, A CORPORATION OF WEST VIRGINIA.

SOFA-BED.

1,299,885.

Specification of Letters Patent.

Patented Apr. 8, 1919.

Application filed July 18, 1914. Serial No. 851,733.

To all whom it may concern:

Be it known that I, LOUIS C. WESTPHAL, a citizen of the United States, residing at Chicago, in the county of Cook and State 5 of Illinois, have invented new and useful Improvements in Sofa-Beds, of which the following is a specification.

This invention relates particularly to such structures as sofa-beds, in which the 10 back is employed as a means for locking the seat in closed position. The primary object of the invention is to provide an improved structure of this character which can be manufactured cheaply, which is operated in a very simple manner, and which 15 is not likely to get out of order.

The invention is illustrated in the accompanying drawings, in which—

Figure 1 represents a view of the 20 proved structure in open position, with one frame-end removed; Fig. 2, a broken vertical sectional view of the back of the structure, showing the means for limiting the forward movement of the spring-actuated 25 front section of the back; Fig. 3, a broken vertical section taken as indicated at line 3 of Fig. 5, showing one of the actuating springs for the front back-section; Fig. 4, a view similar to Fig. 1, but showing the 30 structure in closed position; Fig. 5, a broken rear elevational view of the structure; and Fig. 6, a broken rear elevational view of the central portion of the seat-frame.

35 In the construction illustrated, A represents a frame; B, a forwardly invertible seat; C, a folding-bed normally housed in the frame below the seat; and D, a back comprising a fixedly-mounted rear section 40 1 and a spring actuated front section 1^a.

The frame may be of any suitable construction. As shown, it comprises end-standards 2 which afford arms for the sofa; and an open-topped box 3 rigidly secured to 45 the lower portions of the end-standards.

In the illustration given, the seat is connected, by links 4, to brackets 5 secured to the front corners of the box 3, the seat being adapted to swing forwardly from a 50 position in which it surmounts the box 3 to an inverted position in front of the main frame.

In the form illustrated, the folding-bed C comprises a rear-section 6; an intermediate or spacing-section 7, and a front sec-

tion 8, the intermediate section being pivotally mounted on brackets or hangers 9 applied to the corners of the seat-frame. The sections 6 and 8 are pivotally connected with the intermediate section 7. The rear 60 section 6 is connected by elbow-levers 10 to the rear portions of the brackets 5; and the members 10 are joined by links 11 to the brackets 9. The section 8 is connected, by links 12, to the swinging edge-portion 65 of the seat B, and the seat B is equipped with legs 13, operated by links 14. The rear portion of the bed-section 6 is connected, by heavy coil-springs 15, to standards 16 with which the rear corners of the 70 box 3 are equipped. The folding-bed structure and the manner of connecting the same and the seat to the main frame are known in the art.

When the structure is in the folded condition shown in Fig. 2, the springs 15 tend to throw the seat open and aid in unfolding the bed-structure. The section 1^a of the back normally locks the seat against opening. The rear section of the back is 75 in the form of a rectangular frame, which is rigidly secured, as by bolts 17, to the rear portions of the end-standards 2 of the main frame. The end-portions of the back-section 1 are equipped with clips 18 which 80 project forward and support pivots 19 on which the upper portion of the front back-section 1^a is hung. Conical coil-springs 20 are interposed between the frame-members 85 of the front and rear back-sections, the springs 20 tending to throw the lower end of the front back-section forward to the locking position shown in Fig. 4. The forward movement is limited by flexible strips 21 which may be of cloth. These flexible 90 strips are tacked to the lower portions of the back-sections 1 and 1^a, as shown in Fig. 2.

When it is desired to convert the structure from sofa-form to bed-form, all that is necessary is to press rearwardly on the lower 100 portion of the front back-section 1^a. When the front back-section is thus retracted from the locking position, the rear portion of the seat is released, and the springs 15 operate to throw the rear edge of the seat upwardly 105 somewhat and assist in the operation of unfolding the structure. The front back-section returns to its projected position; and when the structure is converted from the bed form to the sofa form, the rear portion 110

of the seat pushes the lower portion of the front back-section out of the way as the seat is pressed to the fully closed position, after which the springs 20 project the front back-section to the locking position. If desired, the operator may press the front back-section rearwardly at the same time that he presses the seat downwardly to the closed position, and may release the back-section at the proper time to permit it to lock the seat in the closed position.

From the foregoing description, it will be understood that the front back-section is normally held yieldingly in an advanced position and is adapted to be retracted by the seat during the closing operation, after which it springs forward to the locking position. The idea of utilizing one section of the back as a fixed section and another section as a spring-actuated locking-section enables the mechanism to be made exceedingly simple and obviates danger of the mechanism getting out of order.

It is desirable to provide the lower portion of the back-section 1^a with an extension or cleat 22 adapted to be engaged by a roller 23 secured by a staple 24 to the central portion of the rear rail of the seat-frame. In the closing operation, the roller will engage 30 the cleat 22 and automatically push the back-

section 1^a rearwardly to prevent the rear edge of the seat from injuring the upholstering at the lower portion of the back-section 1^a. When the roller passes below the plane of the cleat, the back-section 1^a springs forward to the locking position.

The preferred construction has been described in detail for clearness of understanding, and no unnecessary limitation should be understood therefrom.

What I regard as new and desire to secure by Letters Patent is—

In a structure of the character set forth, the combination with a frame, of a forwardly-turning seat, means tending to turn 45 said seat to the open position, a fixedly-mounted rear back-section, a front back-section pivotally supported at its upper portion, a spring interposed between said back-sections and adapted to move the front back-section to the seat-locking position, and flexible connecting-means between the lower portions of the back-sections serving to limit 50 forward movement of the lower portion of the front back-section.

LOUIS C. WESTPHAL.
